PRAYER ALTAR

Irwin William Tucker, Wynnewood, Okla.

Application December 27, 1954, Serial No. 33,712

Term of patent 14 years

(Cl. D29—23)

FIG. 1

The broken lines in the drawing are for the purpose of illustration only.

I claim:

The ornamental design for a prayer altar, as shown and described.
